(57) **CLAIM**

The ornamental design for a box with securing straps, as shown and described.

DESCRIPTION

FIG. 1 is a bottom perspective view of our new design for a box with securing straps comprising a sidewall enclosure and a pair of trays in a fully assembled configuration.

FIG. 2 is a right-side elevation view thereof.

FIG. 3 is a left-side elevation view thereof.

FIG. 4 is a front elevation view thereof.

FIG. 5 is a rear elevation view thereof.

FIG. 6 is a top plan view thereof.

FIG. 7 is a bottom plan view thereof.

FIG. 8 is a top plan view of our new design for a box with securing straps in an unassembled blank configuration.

FIG. 9 is a top plan view of the sidewall enclosure in a blank configuration thereof, shown separately to show aspects of the design that may not be apparent in the other views; and, FIG. 10 is a top plan view of a lower tray of the pair of trays in a blank configuration thereof, shown separately to show aspects of the design that may not be apparent in the other views.

Those features shown in equal length broken lines depict portions of the box with securing straps that form no part of the claimed design. Those features shown in dash-dot broken lines depict bend lines that form no part of the claimed design.
